PEG GAME BOARD

Gordon E. Kaye and Herbert Jacobel,
Westchester County, N. Y.

Application October 12, 1953, Serial No. 27,141

Term of patent 7 years

(Cl. D34—5)

To all whom it may concern:

Be it known that we, Gordon E. Kaye, a citizen of the United States, residing in the county of Westchester, State of New York, and Herbert Jacobel, a citizen of the United States, residing in the county of Westchester, State of New York, have invented a new, original, and ornamental Design for a Peg Game Board, of which the following is a specification, reference being had to the accompanying drawing, forming a part hereof.

The single figure is a perspective view of the peg game board showing our new design.

We claim:

The ornamental design for a peg game board, substantially as shown.
